UNITED STATES PATENT OFFICE.

HANS KREIDEL, OF WIESBADEN, GERMANY.

HAND-OPERATED GREASE GUN.

Application filed June 13, 1927, Serial No. 198,395, and in Germany June 10, 1925.

All known hand actuated high pressure lubricating guns have the defect that they are not sufficiently fluid tight when applying high pressures and when using consistent 5 or liquid lubricants for example grease or oil, or when placed or held in different positions of operation. In order to overcome this objection, I construct the packings between the main piston and the lubricant container, the working cylinder and its guide piece, and between the plunger and the working cylinder in such a manner that the lubricating gun operates efficiently in all positions and when using various kinds of lubricants 10 even when applying the maximum pressure.

Instead of providing the main piston of the container with the usual cup leather packing it is provided with a packing the marginal portion of which is adapted to 15 spread. To the main piston is secured a disc of leather or the like of which the diameter is only slightly larger than the internal diameter of the supply container so as to form a marginal portion adapted to 20 spread. To the main piston is secured a disc of leather or the like of which the diameter is only slightly larger than the internal diameter of the supply container so as to form a marginal portion adapted to 25 spread and whilst the main piston can be easily moved forwardly it can be moved in the opposite direction only with difficulty. During the forward movement of the piston, 30 said flexible disc of leather or the like will engage the inner surface of the container along a single line formed by one of the edges of said marginal portion, the other edge of said portion being out of contact with the container. If however the weight 35 or the resistance of the lubricant exerts pressure in such a direction as tend to arch or bend the marginal portion of said disc, both edges of said portion, and the entire peripheral surface of the disc, between said 40 edges, in other words, a surface corresponding to the full thickness of the disc, will be pressed against the inner wall of the cylindrical container and thus presents a considerable resistance to movement of the 45 main piston in the direction of the action of the weight of the lubricant thus producing a very tight joint. The greater therefore the weight of the lubricant the higher will be the pressure acting upon the edge of 50 the packing disc and thus more efficient the packing and the greater will be the braking action applied to the main piston. A small chain secured to the main piston serves to enable the latter to be withdrawn from the 55 container when this is to be refilled. In order that this may be readily effected I have provided means for suspending the braking action of the flexible disc and for this purpose the flexible disc is not directly secured to the main piston but to a spring 60 bolt guided in the piston and connected to the chain. By pulling this bolt the disc is raised from the main piston and is arched upwardly by reason of the resistance at the edge. In this position there will not be any 65 considerable resistance to the withdrawal of the main piston. The working cylinder which moves relatively to the stationary plunger is outwardly packed by an elastic packing fitted into its guide piece and upon 70 which there is constantly exerted the pressure of its return spring, whilst the packing of the plunger against the interior of the actual pressure chamber of the working cylinder is effected by a packing ring, of 75 elastic material, for example leather or the like, clamped in its cylinder head, which packing ring projects freely inwardly and covers in the manner of a diaphragm an enlargement of the cylinder neck which is 80 preferably in the form of a funnel and enlarged towards it. A portion of the lubricant enclosed in the pressure chamber of the working cylinder will endeavour to escape rearwardly when the lubricating gun 85 is pressed upon the part to be lubricated or the lubricating nipple thereof and the plunger is thus forced into the pressure chamber of the working cylinder, where the lubricant will be held back by the elastic 90 packing ring and by a pressure acting thereon which is gradually increased, in accordance with the increase of the pressure in the pressure chamber of the working cylinder. By the compression of the packing 95 ring the vertical wall of its circular aperture is thus pressed against a periphery of the plunger and surrounds this in a fluid tight manner so that no lubricant can return into the container and on the subsequent movement of the working cylinder on the plunger a high and effective vacuum is produced in the pressure chamber thereof. As in the case of an increase of working pressure in the pressure chamber the annular wall of 100 the elastic packing ring is always pressed more tightly against the plunger, the pressure on the packing which forms the joint between the working cylinder and its guide member, automatically increases with the increased tension of the return spring.

The accompanying drawing illustrates in

longitudinal section one example of a construction according to the invention.

Figure 1 shows the high pressure lubricating gun in the inoperative position.

5 Figure 2 shows it in the operative position with the plunger in the lowest position, and

Figure 3 shows the main piston with the packing disc when being withdrawn from 10 the supply container.

The lubricant container *a* is provided with a main piston *b* and a removable filling cover *c*, which latter is provided with a small air inlet hole. On the side of the main piston 15 *b* facing the cover *c* there is secured, by means of an outwardly dished rigid metal disc *b'*, a second disc *b*² of hard leather or other flexible material suitable for the purpose. This disc *b*² is only slightly larger 20 than the internal diameter of the supply container so that its marginal portion will arch in the manner indicated in Figures 1 and 2 and will normally have a line contact along one edge with the inner wall of the container. When pressure is exerted by the lubricant in the container on the main piston *b* in the direction towards the cover *c* the marginal portion of the disc *b*² spreads and bears 25 firmly against the inner wall of the container with the full peripheral surface of said disc thus forming an effective joint. For the purpose of withdrawing the main piston from the container I provide a small chain which, when the lubricating gun is ready for 30 operation, is adapted to be accommodated in the space between the cover and the main piston. In order that this withdrawal may be readily effected the disc *b*² is not secured to the main piston itself but to a spring bolt 35 *b*³ guided in the main piston and having the chain attached thereto, said disc *b*² being held between a collar on the spring bolt and the clamping plate *b'*. Normally the flexible disc *b*² is pressed upon the side of the 40 main piston facing the cover *c* by the action of the spring bolt *b*³. By pulling the chain of the spring bolt and thereby compressing the spring of the latter the disc *b*² is arched and separated from the piston at 45 the center by reason of the resistance at the edge thereof. In this position it no longer opposes any considerable resistance to the withdrawal of the main piston (see Figure 55 3). Whenever the pull upon the chain of the spring bolt *b*³ ceases the spring will expand and again draw the disc *b*² into its normal position on the face of the main piston.

In the reduced neck of the lubricant container *a* is fitted a closing member *d* having a cap secured thereto which freely projects into the container.

To the cover of this closing cap is secured the plunger *e*. Lateral apertures *f* in 60 the cap establish communication between the

container and the gun mechanism proper and permit the passage of the lubricant. A guide member *g* screwed into the closing member *d* serves to guide the working cylinder *h* which is adapted to slide axially in 70 relation to the plunger *e*. The rear part of the working cylinder forms the pressure chamber proper *h'*. The free end of the tubular extension *h*² of the working cylinder is provided with a nozzle *i* for application 75 to the part to be lubricated. The top of the pressure chamber *h'* is open towards the plunger *e* while at the bottom said chamber has an outlet aperture *h*³ which is closed by a non-return valve *k* mounted in the tubular 80 extension of the working cylinder. The strengthened cylinder head *h*⁴ which projects into the closing member *d* limits the movement of the working cylinder in the guide member. A return spring *l* is coiled 85 around the working cylinder and at one end bears against the nozzle *i* and at the other end against the guide member *g*. A protecting cap *m* is adapted to be fitted over the front end of the lubricating gun when 90 this is not in use and is adapted to be screwed on the external screw thread of the guide member *g*. For the purpose of providing a tight joint between the working cylinder and its guide member there is provided in the latter, in accordance with the invention, an elastic packing *n* which is preferably always under the pressure of the return spring *l*, and for establishing a tight 95 joint between the plunger *e* and the pressure chamber of the working cylinder a packing ring *o* of elastic material, for example leather, is clamped in the top of the pressure chamber in such a manner that the wall 100 of its circular opening slides closely and tightly on the surface of the plunger when this passes therethrough during the operation of the gun.

Adjacent to the packing ring *o* which is held in position by means of a metal ring *p*, over which the end of the working cylinder is spun, the pressure chamber *h'* is provided with a short enlarged portion *r* in which collects the lubricant which tends to escape rearwardly whilst the working cylinder is being drawn over the plunger and exerts a high surface pressure upon the free annular edge of the ring, which pressure increases with the working pressure. By reason of the resultant compression of the elastic ring, which is firmly clamped on the outside, the passage therein is somewhat reduced and consequently the ring always bears tightly around the plunger.

For the operation of the high pressure lubricating gun, this, as shown in Figure 2, after the removal of the protecting cap *m*, has its nozzle applied to the part to be lubricated and the container *a* is then pressed inwardly by hand. The return spring *l* is 125 130

thus tensioned and the pressure chamber h' of the working cylinder h filled with lubricant moves along the plunger e , the non-return valve k opens and allows the lubricant 5 to escape, the lubricant being applied to the part to be lubricated under pressure through the nozzle i . As soon as the position shown in Figure 2 has been reached, the gun thus completely collapsed, the non-return valve k again closes. Whilst the return spring l expands and the plunger e is withdrawn from the pressure chamber h' of the working cylinder a vacuum is produced by which, as soon as the packing ring o leaves the plunger 10 e , fresh lubricant is drawn from the container a into the pressure chamber. The atmospheric pressure acting upon the main piston b in the container thus moves the main piston forwardly in the container a 15 distance corresponding to the quantity of lubricant which has been drawn into the pressure chamber.

By reason of the means employed for obtaining a tight joint between the working 20 cylinder and the guide member, as also between the pressure chamber of the working cylinder and the plunger, this action is also effectively maintained continuously even when using very consistent lubricants. 25 When withdrawing the tightly clamped packing ring from the plunger the comparatively high vacuum produced in the pressure chamber is destroyed so suddenly that the lubricant is projected from the container 30 into the pressure chamber in the manner of a recoil. It is pressed from this chamber by reason of the tight joint between the pressure chamber and the plunger, as also by reason of the impossibility of backward flow, 35 therefore without any influence on the quantity, even under very high pressure, so that provision is made for a constant complete and uniform supply of lubricant to the part to be lubricated.

40 By reason of the particular packing of the main piston this piston is drawn up readily after each stroke of the gun whilst entirely excluding air and at the same time preventing the passage of lubricant to the 45 nozzle which has been removed from the part to be lubricated or during the movement in the opposite direction, when the container is at the bottom, as the weight of the lubricant bearing thereon causes the edge of the 50 flexible disc b^2 to be pressed firmly and tightly against the inner wall of the container.

Having thus described my invention what

I claim as new and desire to secure by Letters Patent is:—

1. In a lubricant gun, a lubricant container having a cylindrical inner wall, a piston slideable therein and provided with an aperture, a bolt mounted in said aperture, a rigid disc secured to said bolt, resilient means urging said rigid disc toward said piston, and a flexible disc between said rigid disc and said piston, said flexible disc being of slightly greater diameter than the interior of said container and having its edge normally upturned and engaging said inner wall.

2. In a lubricant gun, a lubricant container having a cylindrical inner wall, a piston slideable therein, a flexible disc overlying said piston and normally contacting therewith, said flexible disc being of slightly greater diameter than the interior of said container and having its edge normally upturned and engaging said inner wall, a bolt reciprocably mounted in said piston and fixed to said disc, and resilient means urging said bolt and said disc toward said piston.

3. In a lubricant gun, a lubricant container having a cylindrical inner wall, a piston slideable therein, a flexible disc overlying said piston and normally contacting therewith, said flexible disc being of slightly greater diameter than the interior of said container and having its edge normally upturned and engaging said inner wall, a rigid disc overlying said flexible disc, a bolt reciprocably mounted in said piston and fixedly secured to said disc, resilient means urging said bolt and said disc toward said piston, and means secured to said bolt or moving the bolt and the disc away from said piston.

4. In a lubricant gun, a lubricant container having a cylindrical inner wall, a piston slideable therein, and a flexible disc connected with said piston and overlying it, said disc being of slightly greater diameter than the interior of said container and having its marginal portion normally upturned and in line contact only, along one of its edges, with said inner wall, said marginal portion being adapted, upon movement of the piston in one direction, to spread so as to establish surface contact of said portion with said inner wall on the entire peripheral surface of the disc throughout the thickness of the disc.

In testimony whereof I affixed my signature.

HANS KREIDEL.
